UNITED STATES PATENT OFFICE.

FRANK D. KNIGHT, OF HUDSON, MASSACHUSETTS.

SAFETY-CAR.

SPECIFICATION forming part of Letters Patent No. 365,309, dated June 21, 1887.

Application filed March 12, 1887. Serial No. 230,700. (No model.)

To all whom it may concern:

Be it known that I, FRANK DAVID KNIGHT, a citizen of the United States, and a resident of Hudson, in the State of Massachusetts, have 5 invented certain new and useful Improvements in Means for Preventing the Derailment of Cars; and I do declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 Figure 1 of the drawings is a side view of a car-truck with my invention attached. Fig. 2 is a bottom view of a car-truck with my invention attached. Fig. 3 is a vertical longitudinal section of runner. Fig. 4 is a cross-section of runner.

20 This invention has relation to devices to prevent the derailment of railroad-cars, and its object is to avoid the deplorable casualties which arise from raised or broken rails, misplaced switches, broken wheels or journals, &c.

25 In the accompanying drawings, the letter A designates a car-truck, and B B the axle-boxes.

C C are the wheels, and D D the journal portion of the axles E E.

30 P P are the pedestals or frame-castings in which the axle-boxes are located.

35 F F indicate the flanged runners or shoes, which are shown as applied to each wheel separately, but which may be made longer and larger and applied to all the wheels on one side of the truck, a slot being provided for each wheel. The runner or sled shoe F may be made in different forms, according to the style of truck, but its principal features will exist 40 in each form. The runner is constructed with a smooth base portion, G, which is rounded or curved upward at each end, so that it will take in the end of a displaced or broken rail, should such rail happen to be raised four inches

45 above the ordinary level; and the base is slotted to allow the wheel of the car to extend downward through it to the track, as indicated at H. The base is made considerably wider than the wheel, so that there is a sliding surface, as indicated at K, on each side of the wheel wide enough to catch on the rail in case the wheel 50 leaves the track, or to embrace the laterally-

deflected end of a rail, or of a broken part thereof, whether the deflection be on one side or the other of the approaching wheel. This 55 runner or shoe is formed with the catch-flanges L on each side, extending upward and outward along the edges of the curved ends, as shown. From the shoe extends upward a short outer standard or bearing, N, which is designed to 60 be bolted to the bottom of the pedestal or box-casting P. Inside or back of the wheel is formed the long standard attachment-column S, which extends upward and is provided with a catch-bearing for the axle of the wheel, as 65 indicated at Z, and is bolted to the inner timber, T, or other fixed portion of the truck-frame back of the wheel.

70 In case of an accident where the wheels of the truck leave the track the shoes catch 70 thereon at once, and the wheel coming down, because of the falling journal, in the slot, which is made of less size than a section of the wheel below the center, and preferably of similar form, fills the slot and braces the runner, so 75 that the car slips along on the rail until the train is stopped, the friction between the runner and rail aiding in the braking. So, also, in case of an accident on account of a broken or misplaced rail, when the wheel leaves the 80 track the runners will slide forward, and, embracing the broken or displaced end of the rail in front, will draw it inward, catch again, and allow the car to slide on the rails until stopped. In case of a misplaced switch, the 85 outwardly-extending flanges of the shoe will draw the switch-rails to place before the wheels come upon them; and if a journal should break the weight of the car brings the shoe to bear, the wheel moving upward in the slot of the 90 shoe. At the same time the bearing back of the wheel secures the axle-shaft.

Having described this invention, what I claim, and desire to secure by Letters Patent, is—

95 1. A safety-catch runner for railway-trucks, having a slot, through which the wheel projects downward, of less size than a section of the wheel below the center, and on each side of said slot guiding-surfaces curved upward 100 at their ends and provided with edge flanges extending upward and outward along the arms, said runner being provided with standards of unequal height, one outside of and the other

back of the wheel, where it is adapted to fit under the box-frame and under the timbers of the truck, substantially as specified.

2. A safety-catch runner for a railway-truck, 5 having a slot through which the wheel projects downward, bearing surfaces on each side of said slot, having edge flanges and standards of unequal length, one adapted to fit under the box-frame and the other having a vertically-10 extended shaft slot or opening under the timbers of the truck, substantially as specified.

3. The combination, with a slotted flanged 15 safety-runner having a short outer pedestal standard or bearing and a long inner standard formed with a vertically-extended axle slot or opening, of the wheel, its shaft, the boxing,

frame, casting, and the attachments thereof, substantially as specified.

4. The combination, with the car-truck and a vertically-movable axle in connection therewith, carrying the wheels, of a safety-runner attachment rigidly connected to the truck and slotted for the wheels to project through and to allow play for the axle, substantially as specified. 20 25

In testimony whereof I affix my signature in presence of two witnesses.

FRANK D. KNIGHT.

Witnesses:

PHILIP C. MASI,
THEO. MUNGEN.
